UNITED STATES PATENT OFFICE.

ISIDOR J. KUSEL, OF CHICAGO, ILLINOIS, ASSIGNOR TO STRONGHART COMPANY, OF CHICAGO, ILLINOIS, A CORPORATION OF ILLINOIS.

COIN BANK.

Application filed January 5, 1920. Serial No. 349,466.

To all whom it may concern:

Be it known that I, ISIDOR J. KUSEL, a citizen of the United States, residing at Chicago, in the county of Cook and State 5 of Illinois, have invented a certain new and useful Improvement in Coin Banks, of which the following is a full, clear, concise, and exact description, reference being had to the accompanying drawing, forming 10 a part of this specification.

My invention relates to coin banks adapted for receiving and saving coins particularly of the smaller denominations.

One of the objects of the invention is to 15 provide an arrangement by which a coin may be inserted into the bank but may not be withdrawn from the same, and to prevent such withdrawal while the coin is in process of being inserted.

20 Another object of the invention is to provide an arrangement by which a coin while being inserted may not be withdrawn by the assistance of another coin or some other object.

25 Another object of the invention is to accomplish the foregoing and other desirable results in a simple and expeditious manner.

In the accompanying drawings Fig. 1 is a 30 plan view of a coin bank embodying my present invention;

Fig. 2 is a side elevation of the same with a portion of the bank broken away along line 2—2 in Fig. 1;

Fig. 3 is a cross section taken on line 3—3 35 in Fig. 2.

In the drawings I show a bank A which may be of any suitable size and construction. The bank shown is of generally old form with a bottom 1 and top 2. The top 2 is 40 provided with a longitudinally extending coin slot 3 into and through which the coins are to be inserted.

As an arrangement for automatically permitting the insertion of the coins and preventing their withdrawal, I show a plurality of spring clips 4—4 arranged in rows on opposite sides of said slot 3. The spring clips or members 4—4 in one row are preferably staggered with reference to those in 50 the other row as well shown in Fig. 1, in which case the clips in one row will be located substantially opposite the spaces in the other row.

These clips 4—4 are preferably held in

proper position by means of plates 6 and 7 55 secured to the under side of the top 2, as by means of rivets 8—8, the clips 4—4 being interposed between said plates and said top 2. The clips 4—4 in their normal position are in contact with the lowermost portion 60 of the inturned edges 2^a—2^a of the slots.

As a preferred arrangement the adjacent ends of the plates 6 and 7 are turned or bent downwardly as shown in Fig. 3, so as to serve as guards or abutments for limiting 65 the downward movement of the clips 4—4.

In using the bank, a coin will be inserted into the slot 3 and will strike against the somewhat down-turned ends of the members 4—4 and will push said members downwardly so as to allow the coin to move into the bank. After passing between the ends 70 of the members 4—4 the coin will drop into the bank. If during the insertion of the coin effort is made to pull it back, that cannot be accomplished because the ends of the members 4—4 will engage the coin, will be drawn together and against the inturned edges 2^a—2^a, by such outward pull of the 75 coin, there being something of a clamping or gripping action holding the coin against withdrawal.

This gripping of the coin will take place to effectively prevent its withdrawal irrespective of the extent to which the coin has been inserted, that is whether it has 80 been inserted much or little. After the coin has been inserted and has dropped to the floor of the bank, it cannot find its way 85 out of the coin slot because the ends of the members 4—4 are so close together as to prevent the coin passing between them in an outward direction.

Should effort be made to release a coin in process of being inserted by means of another coin slipped into the coin slot beside the first one, or by means 90 of some other article introduced that way, the guard members 6 and 7 will hold the clips 4—4 against such extended downward and sidewise movement as to allow the coins to become loose between the spring clips 95 sufficiently to be withdrawn. In other words the guard members 6 and 7 tend to stiffen and strengthen and back up the spring clips 4 when the same are pressed downwardly and inwardly to an undue extent. Thus tampering with the device to release a coin after it has been partly or 100 completely inserted is also prevented.

It will be understood that changes and modifications may be made without departing from the spirit of the invention.

What I claim is:

- 5 1. A coin bank having a coin slot the edges of which extend downwardly, spring coin engaging slips arranged in rows along opposite edges of the coin slot, said clips extending substantially to the middle portion 10 of the slot and being normally in contact with the lowermost part of the edges of the coin slot, whereby the clips yield downwardly to permit insertion of a coin between the rows of clips and are held by the edges of 15 the slot against movement upwardly from their normal position.
- 20 2. A coin bank having a coin slot the edges of which extend downwardly, spring coin engaging slips arranged in rows along the opposite edges of the coin slot, the clips in one row being staggered relatively to those in the other and normally in contact with the lowermost part of the edges of the slot, said clips extending downwardly and 25 inwardly so as to substantially close the slot the clips yielding downwardly to permit insertion of a coin between the rows of clips and being held by the edges of the slot against movement upwardly from their normal 30 position.
- 35 3. A coin bank having a coin slot with downwardly turned edges, a pair of downwardly curved guard members mounted on opposite sides of the slot, said guard members being mounted on the wall of the bank in which said slot is located, and a pair of downwardly curved resilient coin engaging clips interposed between said guard member and said slot and normally in contact 40 with the lowermost portion of the edges of the slot, said clips extending past the edges of the slot, so as to substantially close the slot, and yielding downwardly to permit the insertion of a coin through the 45 slot.
4. A coin bank having a coin slot with downwardly turned edges, a pair of downwardly curved guard members mounted on

opposite sides of the slot, said guard members being mounted on the wall of the bank 50 in which said slot is located, and a pair of coin engaging clips interposed between the guard members and the wall containing said slot, said guard members and clips being fastened to said wall by means of rivets passing through said guards, clips and wall, the clips being bent downwardly to substantially larger radii of curvature than the guard members, said clips being normally in contact with the lowermost portion of the edges 60 of the slot and substantially closing the slot and yielding downwardly to permit insertion of a coin in the slot.

5. A coin bank having a coin slot with side edges extending downwardly and provided with coin engaging devices arranged to extend across the coin opening in rows on opposite sides of the coin slot and in contact with said downwardly extending edges of said coin slot, the devices in one row being staggered with reference to those in the other, in combination with guard members arranged along the edges of the slot underneath said coin engaging members.

6. A coin bank having a coin slot the side 75 edges of which are extended downwardly in combination with spring coin engaging clips arranged to extend across the coin opening in rows along the opposite edges of the coin slot, the clips in one row being staggered relatively to those in the other, and being in contact with the downwardly extending portions of the coin slot, guard members extended along the opposite sides of the coin slot and secured to the wall of the bank in 80 which said slot is located by means of rivets passing through said guards and also through said wall, said clip members being held in position by being interposed between said wall and guards and said guards having 85 inwardly extending edge portions located adjacent said clip ends.

In witness whereof, I hereunto subscribe my name this 12th day of December, A. D., 1919.

ISIDOR J. KUSEL.
